UNITED STATES PATENT OFFICE.

STANLEY PACHNER, OF DRESDEN, KANSAS.

RADIATOR.

Application filed February 17, 1925. Serial No. 9,762.

To all whom it may concern:

Be it known that I, STANLEY PACHNER, citizen of the United States, residing at Dresden, in the county of Decatur, in the State of Kansas, have invented certain new and useful Improvements in Radiators, of which the following is a specification.

My invention relates to improvements in radiators adapted for use in conjunction with the cooling systems of internal combustion engines and the like.

It is an object of the invention to provide a rotatable agitator within the radiator through the medium of which the water is thoroughly circulated within the radiator, insuring cooling of the same before being returned to the motor.

A further object of the invention is to provide a radiator having an upper and lower chamber and cooling tubes between the chambers, with means for conducting the water from the upper chamber to the cooling tubes including a rotatable shaft having a series of radiating discharge pipes adapted to circulate the water in the passage surrounding the cooling tubes.

Another object of the invention is to provide a device of the above-mentioned character which is simple and durable in construction, efficient in operation and inexpensive to manufacture.

Other objects and advantages of the invention will be apparent during the course of the following description.

35 In the accompanying drawings, forming a part of this specification and in which like numerals are employed to designate like parts throughout the same,

Fig. 1, is a side elevation of my invention 40 showing it applied to a motor,

Fig. 2, is a front elevation of the same,

Fig. 3, is a side elevation in vertical section,

Fig. 4, is a rear view partly in section,

45 Fig. 5, is a detail front view of the water circulating device, and,

Fig. 6, is a fragmentary longitudinal sectional view of the rotary shaft.

In the drawings, wherein for the purpose 50 of illustration I have shown a preferred embodiment of my invention, the numeral 5 denotes, generally, the body of my improved radiator which is preferably constructed of sheet metal. The body has a relative large tapered opening 6 through the center thereof with chambers 7 and 8 at the top and bot-

tom. A series of rows of spaced vertical tubes 9 are mounted within frusto-conical shaped band 9', and the band is disposed within the front part of the opening 6, being secured in spaced relation thereto, by the angular flanges 10', extending upwardly from the front edge of the band and bolted to the front wall of the radiator, as at 11'. Thus, it is seen that an annular passage 10, surrounds the band, with which the upper and lower ends of the tubes 9 communicate. The upper chamber 7 has a lateral extension 7' projecting from the rear of the radiator and which is connected with the motor 11 by the pipe 12. A pipe 13 depends from the bottom of the extension having a transverse opening 14 through its lower end to receive the rotary tubular shaft 15 which has one end journaled therein, by the flange 16 and a washer 16' provides a water tight connection between the shaft and its bearing. The opposite side of the opening is closed by the plate 17. The shaft is supported by the hanger 18 depending from the extension 7' 50 and has its forward end journaled in the bearing 19 of the spider 20 mounted in the inner end of the opening 6. Movement is imparted to the shaft through the medium of the belt 21 which is trained over the pulley 22, mounted on the shaft between the pipe 13 and hanger, and a pulley mounted on the drive shaft of the engine. A fan 22' is mounted on the shaft between the hanger and spider to create a circulation of air 55

through the opening 6 of the radiator. The forward end of the shaft 15 projects within the opening 6 having a cone shaped cap 23 mounted thereon, from which the water circulating pipes 24 radiate. The pipes 24 are arranged in a series of four each, disposed in parallel relation and positioned at equal distances about the circumference of the cap 23. The free ends 25 of the pipes are slightly curved outwardly and are mounted in the circular plate 26 which is disposed with the annular passage 10 closing the inner side thereof. The lower chamber 8 communicates with the annular passage 10, so the water discharged from the pipes 24 will pass down the tubes 9 into the lower chamber where it is returned to the motor. 60

In operation, the water in the upper chamber is conducted to the rotary shaft 15 by the pipe 13 and through centrifugal force, caused by the rotation of the shaft, is discharged through the radiating pipes 24 65

into the annular passage 10. The rotation of the shaft will create a circulation of water within the passage and through the tubes 9, causing it to be thoroughly cooled by the air passing around the tubes which is drawn through the radiator by the fan. Thus it is seen that the water is properly cooled before it is deposited into the lower chamber where it is returned to the motor.

10 It is to be understood that the form of my invention herewith shown and described is to be taken as a preferred example of the same and that certain changes in the shape, size and arrangement of parts may be made 15 without departing from the spirit of the invention or the scope of the subjoined claims.

Having thus described my invention, I claim:

- 20 1. A radiator including a body having a central opening and upper and lower water chambers, a series of tubes disposed within said opening, having their ends opening into an annular passage surrounding said tubes, a rotary tubular shaft disposed axially with respect to said opening, means for conducting the water from said upper chamber to said shaft, a series of pipes radiating from the free end of said shaft having their discharge ends disposed within said passage 30 adjacent the ends of said tubes and means for rotating said shaft.
- 25 2. A radiator including a body having a central tapered opening therethrough, an upper and lower water chamber, a series of vertical tubes disposed in the forward part of said opening, surrounded by an annular passage, a pipe depending from said upper chamber to the rear of said body, a rotary tubular shaft disposed axially with respect 35 to said opening and having communication with said pipe, a series of pipes radiating from the free end of said shaft having their discharge ends disposed within said passage,

an annular plate mounted on the ends of said pipes, a fan mounted on said shaft and 45 means for rotating said shaft.

3. A radiator including a body having a central opening and upper and lower water chambers, a series of water tubes disposed within said opening, having their ends 50 opening into an annular passage surrounding said tubes, a tubular shaft mounted in the rear of said body, a series of pipes radiating from said shaft having their free ends disposed within said annular passage adjacent the ends of said tubes, means for conducting the water from said upper chamber to said shaft, and means for revolving said shaft.

4. A radiator including a body having a central opening and upper and lower water chambers, a series of water tubes disposed within said opening, having their ends opening 55 into an annular passage surrounding said tubes, means for discharging and circulating water within said annular passage and means for conducting water from said upper chamber to said first mentioned means.

5. A radiator including a body having a central opening and upper and lower water chambers, a series of rows of water tubes arranged in stepped relation, said tubes having their ends opening into an annular passage surrounding said tubes, a rotatable tubular shaft mounted in the rear of said body, a series of discharge pipes radiating from said shaft having their free ends disposed within said annular passage, an annular plate mounted on the ends of said pipes, 70 means for conducting the water from said upper chamber to said shaft, and means for revolving said shaft.

In testimony whereof I affix my signature.

STANLEY PACHNER.
